189,373

BOTTLE OR SIMILAR ARTICLE

Nathan Lerner, Chicago, Ill., assignor to W. Braun Company, Chicago, Ill., a copartnership

Filed Sept. 14, 1959, Ser. No. 57,551

Term of patent 14 years

(Cl. D58—8)

I claim:

The ornamental design for a bottle or similar article, as shown.
